DESIGN FOR A TIRE TOOL

John E. Lydle, Akron, Ohio, assignor to The Ken-
Tool Manufacturing Company, Akron, Ohio, a
corporation of Ohio

Application August 17, 1944, Serial No. 114,914

Term of patent 14 years

(Cl. D54—13)

To all whom it may concern:

Be it known that I, John E. Lydle, a citizen of the United States and a resident of Akron, in the county of Summit and State of Ohio, have invented a new, original, and ornamental Design for a Tire Tool, of which the following is a specification, reference being had to the accompanying drawing, forming part thereof.

In the drawing:

Figure 1 is a front elevation of a tire tool showing the new design;

Figure 2 is a side elevation thereof; and
Figure 3 is a rear elevation thereof.

What I claim is:

The ornamental design for a tire tool, as shown.

JOHN E. LYDLE.
